(57) **CLAIM**

The ornamental design for a lamp, as shown and described.

DESCRIPTION

FIG. 1 is a bottom perspective view of a lamp showing my new design;

FIG. 2 is a top plan view thereof;

FIG. 3 is a bottom plan view thereof;

FIG. 4 is a side view thereof, the views from other sides being identical due to the lamp's symmetry about a vertical axis;

FIG. 5 is a partially-exploded bottom perspective view thereof, showing one of five identical shades exploded from the lamp;

FIG. 6 is a bottom perspective view of the exploded shade of FIG. 5;

FIG. 7 is a top perspective view thereof;

FIG. 8 is a top plan view thereof;

FIG. 9 is a bottom plan view thereof;

FIG. 10 is a left side view thereof;

FIG. 11 is a right side view thereof;

FIG. 12 is a front view thereof; and,

FIG. 13 is a rear view thereof.

FIGS. 1, 4, and 5 include break lines and those portions of the article between the break lines form no part of the claimed design. The short broken lines represent environmental subject matter and form no part of the claimed design.
